TABLE

Milton B. Smith, Perrysburg, Ohio, assignor to
The Hetrick Manufacturing Company, Toledo,
Ohio, a corporation of Ohio

Application July 18, 1934, Serial No. 735,723

4 Claims. (Cl. 311—35)

This invention relates to articles of furniture, but particularly to a table which can be readily assembled and disassembled, inexpensive to manufacture, and can be readily and conveniently compacted for storage or shipment.

Other objects and advantages of the invention will hereinafter appear, and an embodiment of the invention is shown by way of illustration on the drawing, in which:

10 Figure 1 is a perspective view of the table mounted in position for use;

Figure 2 is a transverse sectional view on the line 2—2 of Figure 1 showing the underside of the table top and the manner in which the legs are 15 connected thereto;

Figure 3 is an enlarged section through a portion of the table showing the manner in which the legs are attached to the underside of the table;

20 Figure 4 is a sectional view on the line 4—4 of Figure 3;

Figure 5 is an enlarged sectional view showing the manner in which the intermediate portion of the legs are detachably connected together;

25 Figure 6 is a perspective view showing the connection between one pair of legs; and

Figure 7 is a perspective view showing the connection between the other pair of legs.

The illustrated embodiment of the invention 30 comprises a table having a metal top 10 of circular form provided with a depending flange 11 around the periphery thereof. The table top 10 is supported by legs which are arranged in pairs, legs 12 and 13 arranged in opposed relation constituting one pair, and legs 14 and 15 also arranged in opposed relation constituting the other pair.

The legs are of metal tubes and the upper end portion of each leg is provided with an approximately horizontal portion 16 from which extends 35 a downwardly and inwardly inclining portion 17. The intermediate portions 18 of the several legs are in juxtaposed relation, and from this point each leg is provided with an outwardly curved portion 19 and thence an outwardly extending portion 20, which inclines slightly downwardly and at the end of this portion substantially vertically disposed feet 21 are provided. This provides a very substantial support for the table top 10, and also presents a pleasing appearance 40 as well as provides ample leg room beneath the table top.

The intermediate portions 18 of the legs 12 and 13 are rigidly secured together by a tubular member 22 which is secured to the adjacent leg 45 by welding 23. Connecting the pair of legs 14

and 15 is a tube 24 which is slightly larger than the tube 22, this tube likewise being secured to the adjacent legs by welding, or other suitable means. Formed in opposed relation and on the free sides of the tube 24 are elongate slots 25, the 5 lower ends of which are open.

The pairs of legs may be readily assembled to position of use by holding the leg assembly 12—13 upright and then sliding the leg assembly 14—15 thereover with the tube 24 sliding over outside of 10 the tube 22, the slots 25 registering and sliding over the welded portions 23. This interfitting connection of the intermediate portions of the legs securely and satisfactorily holds the legs in 15 assembled and properly spaced relation.

The upper ends of the legs are attached to the underside of the table 10 in an exceedingly simple manner. As most clearly shown in Figure 4, four sheet metal brackets 26 are secured to the flange 11 of the top by rivets 27, one bracket being provided for the end portion of each leg and arranged in equi-distantly spaced relation, as shown on Figure 2. Each bracket 26 has an inwardly extending flange 28 provided with a downwardly pressed portion 29 to provide with the underside of the table top 10 a pocket 30 to receive a flattened end 31 of the respective leg. It will be understood that the upper end portions of the several legs are resilient, the intermediate portion thereof being anchored. Consequently, in attaching the legs to the top, the legs are flexed inwardly to clear the inner edge of the flange 28 and thereafter forced into the respective pocket 30. Assembly of the legs and top can be more conveniently formed by laying the top 10 on the floor with the underside upward, and then by inverting the leg structure the end portions of the several legs can be flexed into their respective pockets 30 without difficulty.

It will be apparent that the table can be readily assembled and disassembled, and when the parts are disassembled the legs can lie substantially flat on the top 10 and in the plane thereof so that the parts can be conveniently packaged.

It is to be understood that numerous changes in details of construction, arrangement and choice of materials may be effected without departing from the spirit of the invention, especially as defined in the appended claims.

What I claim as new and desire to secure by 50 Letters Patent is:

1. A table comprising a top, legs arranged in pairs, a detachable connection between each pair of legs, a pocket on the underside of said table 55 for the upper end of each leg, the upper portions

of said legs being resilient and normally extending beyond said pockets whereby upon inward flexing movement of said legs the same may be inserted respectively into said pockets.

5 2. A table comprising a top, two pairs of legs, a telescoping connection for intermediate portions of said pairs of legs, and cooperating attaching devices on the under side of said top and the upper ends of said legs, the upper portions of 10 said legs being resilient to flex into and out of operative engagement with said top.

3. A table comprising a top, a plurality of legs, means connecting opposed pairs of legs, a detachable connection between said pairs of legs, 15 the upper ends of said legs being resilient, and cooperating attaching devices between said legs and said top enabling connecting same upon inward flexing of said legs.

4. A table comprising a top, legs arranged in pairs, a tube connected at opposed points to one pair of legs, a second tube adapted to telescope over said first tube and connected intermediate its ends and at opposed parts to another pair of legs, said second tube being slotted longitudinally on opposite sides for a portion of its length to fit over said points of connection between the first tube and the respective legs, whereby when said tubes are telescoped portions of said tubes 10 extend above and below their points of connection to the legs, and a detachable connection between the upper ends of said legs and the top.
